ATTORNEY

UNITED STATES PATENT OFFICE

GEORGE MERRICK RIGGLE, OF WEST LOS ANGELES, CALIFORNIA

DESIGN FOR A LAMP STAND

Application filed September 8, 1931. Serial No. 41,044. Term of patent 14 years.

To all whom it may concern:

Be it known that I, GEORGE MERRICK RIGGLE, a citizen of the United States, residing at 10610 Holman Ave., West Los Angeles, California, have invented a new, original, and ornamental Design for a Lamp Stand, of which the following is a specification, reference being had to the accompanying drawing, forming part thereof.

The figure is a view in perspective of a lamp stand showing my new design.

I claim:

The ornamental design for a lamp stand, as shown.

GEO. MERRICK RIGGLE.
